UNITED STATES PATENT OFFICE.

MICHAEL HANAUER, OF TOLLAND, MASSACHUSETTS.

SAP SPOUT AND COVER.

1,347,270.

Specification of Letters Patent. Patented July 20, 1920.

Application filed January 29, 1920. Serial No. 354,801.

To all whom it may concern:

Be it known that I, MICHAEL HANAUER, a citizen of the United States, residing at Tolland, in the county of Hampden and 5 State of Massachusetts, have invented a new and useful Improvement in Sap Spouts and Covers; and I do hereby declare the following, when taken in connection with the accompanying drawings and the characters of 10 reference marked thereon, to be a full, clear, and exact description of the same, and which said drawings constitute part of this application, and represent, in—

Figure 1, a top or plan view of a sap spout 15 and bucket cover constructed in accordance with my invention.

Fig. 2, a side view of the same.

Fig. 3, a sectional view of the spout showing the hook in position to be engaged with 20 the spout.

Fig. 4, a similar view showing the hook turned in the locked engagement with the spout.

This invention relates to improvement in 25 sap spouts and covers. In collecting sap from trees, it is very essential that rain or melting ice running down the trunk of the tree shall be prevented from entering the sap bucket and the object of this invention 30 is to provide a sap spout with a flange which will prevent water from entering the bucket and also to provide a cover for the bucket and the invention consists in the construction as hereinafter described and particularly recited in the claims.

In carrying out my invention I employ a sap spout 6 having a tapered inner end to enter a bore 7 in the trunk 8 of a tree, the inner end 9 of the spout being closed and 40 provided in its underside with a hole 10 through which the sap may enter the spout, the outer end of the spout being formed with a downwardly curved lip 11. Around the spout is a flange 12 and projecting forward from the flange is a web 13 formed 45 with a hole 14. The upper end of the flange is rolled to form a knuckle 15 which fits between knuckles 16 and 17 in the rear edge of a cover 18 which is of proper size to extend 50 over the top of the usual sap bucket 19

which bucket is suspended by a hook 20 formed with an open eye 21 of proper size to surround the spout forward of the flange. This hook is connected with the spout by turning the hook upward so that the end 22 55 of the eye stands in line with the hole 14, then the hook is turned downward and the end 22 passing through the hole interlocks the hook with the spout. The cover 18 is connected with the flange 12 by a wire pintle 23 and so that the cover may be turned upward against the trunk of the tree against which the rear edge of the cover extends, the central part of the cover being formed with a projection 24 to bear against the tree. 60 Any moisture running down the trunk of the tree will strike the flange 24 and be deflected thereby and prevented from following the spout and dripping into the bucket.

The hook is so firmly engaged with the 70 spout that it is not liable to be accidentally displaced and the cover is readily turned to expose the top of the bucket when desired and prevents any moisture entering the bucket.

I claim:

1. The combination of a spout, with a flange formed integral therewith and with a forwardly projecting web formed with an opening of a hook having an eye, one end 80 of which passes through said opening.

2. The combination with a spout formed with an integral flange provided at its upper edge with a knuckle and with a forwardly projecting web formed with an opening, of 85 a cover formed at its rear end with knuckles on opposite sides of the center, and with a rearwardly extending projection, a pintle extending through said knuckles whereby the cover is hinged to the spout, and a hook 90 having an eye one end of which passes through the opening in the said flange.

In testimony whereof I have signed this specification in the presence of two subscribing witnesses.

MICHAEL HANAUER.

Witnesses:

JAMES E. DEAN,
HENRY HANAUER.
